(57) **CLAIM**

The ornamental design for an expanding lion, as shown and described.

DESCRIPTION

FIG. 1 flat unfolded view of an ornamental design for an expanding lion;

FIG. 2 is an assembled front elevational expanded view thereof;

FIG. 3 is an assembled side elevational expanded view thereof;

FIG. 4 is an assembled rear elevational expanded view thereof;

FIG. 5 is an assembled top view thereof;

FIG. 6 is an assembled bottom view thereof;

FIG. 7 is an assembled front elevational view thereof, shown in an alternative position;

FIG. 8 is an assembled side elevational view thereof; and,

FIG. 9 is an assembled rear elevational view thereof.

The broken lines in FIG. 1 are fold lines which appear as solid lines in other figures when assembled.

1 Claim, 3 Drawing Sheets
